UNITED STATES PATENT OFFICE.

RALPH V. L. HARTLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

MODULATOR CONTROL.

Application filed September 29, 1919. Serial No. 327,329.

To all whom it may concern:

Be it known that I, RALPH V. L. HARTLEY, a citizen of the United States, residing at East Orange, in the county of Essex, State 5 of New Jersey, have invented certain new and useful Improvements in Modulator Controls, of which the following is a full, clear, concise, and exact description.

The present invention relates to the operation of relays in which a plurality of output-frequency components are produced for a given input wave.

A feature of the invention relates to the proportioning of the elements concerned in 15 the operation of known relays or relay systems to emphasize certain of the components and suppress other components.

It has been shown, for instance, in British Patent No. 102,503, that modulators can be 20 made to suppress completely the components of unmodified frequency, i. e., the carrier and the modulating frequencies, if the thermionic devices which constitute the modulator are exactly equivalent. Thermionic devices 25 have been combined for other purposes, such as amplifiers of the push-pull type in which the combination frequencies are suppressed to a large extent, or as harmonic generators. It is generally assumed in all such cases 30 that either the thermionic devices are equivalent or that the suppression of the undesired component is only partial. The equivalency of the thermionic devices is a matter of degree and there may be times 35 when it is essential that the suppression of certain components be as complete as possible; for instance, in secret systems of communication in which a small leakage of a carrier frequency, for example, might serve 40 as a key to the carrier that is being used.

According to the present invention, the various quantities which influence the output current components are proportioned in predetermined manner to control the nature 45 of the output currents. For the purpose of showing how and why these quantities are to be proportioned, a mathematical analysis of the action of the typical thermionic three-electrode relay will be given and reference 50 will be made to the accompanying drawings

in which Fig. 1 gives curves characteristic of the type of relay discussed, and Figs. 2 and 3 give schematic circuit arrangements for the relays.

It has been shown that the output current 55 I from a three-electrode thermionic relay may be quite accurately expressed within certain limits by the equation.

$$I = \alpha \left(\frac{1}{\mu_0} E_B + E_C + E \right)^2 \quad (1) \quad 60$$

where α is a constant depending upon the structure of the relay, μ_0 is the maximum voltage amplification obtainable from the device, E_B is the voltage existing between the anode and the cathode, E_C is the voltage existing between the cathode and the grid electrode, and E is a small correction term to take care of a number of factors, such as contact differences of potential in the relay 70 and the power developed in the filament. For further reference the article by H. J. Van der Bijl in the Physical Review for September, 1918, page 171 et seq., may be consulted. 75

If the external impedance of the relay is so small that the voltage drop, due to the external current, is small in comparison with the impressed voltages, equation (1) may be expressed in the form 80

$$I = \alpha \left(\frac{1}{\mu_0} E_B + E_{C_0} + E + e \right)^2 \quad (2)$$

where E_{C_0} is the normal or steady potential of the grid, i. e. (the voltage of the grid 85 battery if there is one). The portion of expression (2) in the parenthesis is seen to comprise a fixed part consisting of the first three terms and a variable part consisting of the last term. If the fixed part is represented by E and the variable part by e , the current I may be expressed by 90

$$I = \alpha (E + e)^2 \quad (3)$$

where e now represents the impressed variable grid potential for controlling the output current I . This relation holds only for values within certain limits. If $(E + e) < 0$, I is zero for all such values, and if $(E + e)$ is positive and above a certain fairly large 100

value or if very small, the relation does not hold.

If the relay is to be used as a modulator, the input voltage will consist of a carrier wave e_p to be modulated and a modulating wave e_q , or $e = e_p + e_q$ where $e_p = P \cos pt$ and $e_q = Q \cos qt$, P and Q being respectively the maximum amplitudes of the carrier and modulating waves. Substituting in (3) and 10 expanding

$$I = \alpha E^2 + 2\alpha E e_p + 2\alpha E e_q + \alpha(e_p^2 + e_q^2) + 2\alpha e_p e_q \quad (4)$$

The first term αE^2 represents a fixed value 15 and need not be here considered, the second and third terms represent the output of the unmodified carrier and modulating frequencies, respectively, the fourth term represents the double frequencies of the two 20 input waves, respectively, and the last term represents the modulated output current, i. e. a wave of carrier frequency

$$\frac{p}{2\pi},$$

25 the amplitude of which varies in accordance with the wave e_q .

That the fourth term represents the double-frequency components may be seen by 30 considering that

$$e^2 p = (P \cos pt)^2 = P^2 \cos 2pt = \frac{P^2}{2} (\cos 2pt + 1)$$

35 in which $\cos 2pt$ is seen to indicate a frequency double that of the wave $P \cos pt$.

That the last term represents the modulated component may be shown by substituting for $2 e_p e_q$, their equivalents so that 40 the term becomes $2 PQ \cos pt \cos qt$, which by trigonometric transformation becomes

$$PQ \cos(p+q)t + PQ \cos(p-q)t.$$

45 Each term of the last expression represents a wave, the frequency of which is respectively

$$\frac{p+q}{2\pi}$$

50 and

$$\frac{p-q}{2\pi}.$$

55 If q represents a range of frequencies, as in case of the voice, there are, instead of two single side frequencies, two side bands of frequencies, respectively,

$$\frac{p+q}{2\pi}$$

60 and

$$\frac{p-q}{2\pi}$$

65 as is well known, having amplitudes vary-

ing in accordance with the amplitude of the modulating, or voice, wave.

Referring to equation (4), it is seen that the terms representing the unmodified frequencies are dependent on E , while both the 70 double-frequency and modulated components are independent of E . Diminishing E , at least within the limits in which the relation expressed by equation (3) holds, does not therefore affect the output of the combination frequencies but directly decreases the output of the single frequencies. By controlling E , therefore, the relay may be made to act selectively to a certain extent 80 in determining the amount of unmodified carrier frequency or modulating frequency that is to appear in the output circuit.

In Fig. 1 the three curves A, B and C may represent part of the family of characteristic curves for a given thermionic relay, in which the ordinates represent the current between cathode and anode and the abscissæ represent the voltage of the grid with respect to the cathode. The curves A, B and C are obtained by using successively larger plate voltages, and it is obvious that a new curve will be obtained for every different plate voltage that is used. Considering that the portions of curves B and C, lying between the two limits a and b , conform to equation (4), if the grid potential is varied within these limits by the input waves e_p and e_q the output of the combination frequencies will be the same whether the plate voltage is that corresponding to curve B or to curve C, but in case of curve C the output of the unmodified frequencies will be greater. Obviously, then, if either the modulation or the double-frequency output alone is desired for any given grid voltage, the smallest plate voltage that will give the desired output of the modulation or double-frequency component should be used. This will materially cut down the production of the unmodified components. 100 A similar effect will be produced by variation of the normal grid potential, leaving the plate voltage constant. Such variation will not, however, affect the output of the combination frequencies as has often been supposed heretofore, so long at least as the assumed equation holds. Either decreasing the plate voltage or making the grid more negative means a decrease in E .

A practical application of the principles that have been set forth may be realized in a single modulator where a maximum production of modulated output is desired and a normal amount of carrier component. Frequently considerable inefficiency results from the fact that the carrier wave is only partially modulated and needless amounts of the carrier wave are transmitted. In Fig. 2, if the modulator 1 is fed from the source 2 of carrier frequency and with 110 115 120 125 130 135

speech waves from the microphone 3, and if the assumed relation holds, the output will contain all the elements given by equation (4). If the carrier output component 5 is unduly large, by making E small, the output of the unmodified carrier component may be cut down. Also it is shown above that in the output the unmodified components are respectively proportional to P and 10 Q, the double-frequencies are proportional to P^2 and Q^2 respectively, and the modulated component is proportional to PQ. If the smallest value of

$$15 \quad \frac{p-q}{2\pi},$$

i. e., the lowest frequency of the modulated component represented in the lower side band, is greater than the greatest double-frequency of the modulating wave, a filter 20 5 may be used to pass only the carrier wave and the modulated components. By making P small and Q correspondingly larger, the modulated components will be undiminished and the carrier component may be 25 cut down to a desired value. As stated, the output of e_q , e_q^2 , and e_p^2 can, under the conditions assumed, be eliminated by the filter 5.

30 The principles above set forth find greater application where two or more thermionic relays are combined in the form of balanced modulators, amplifiers, etc. There are four ways of applying the same waves e_p and e_q 35 to the respective relays I, II, III and IV as follows:

I	$e_p + e_q$
II	$e_p - e_q$
III	$-e_p + e_q$
IV	$-e_p - e_q$

40 That is, by suitable input connections between the wave sources and the respective relays, one or the other or both impressed voltages may be made opposite in sign on two of the relays. The current i_1 from the

$$i_1 + i_4 = (\alpha_1 + \alpha_4) \left[2E \frac{\alpha_1 - \alpha_4}{\alpha_1 + \alpha_4} (e_p + e_q) + e_p^2 + e_q^2 + 2e_p e_q \right] \quad (6)$$

This equation would eliminate both unmodified components if both relays had the same α value and would be useful where such elimination is desirable but where a filter 95 could not be used to separate the modulation component from the input frequencies. Such a case would be where some of the lower modulation frequencies

$$100 \quad \frac{p-q}{2\pi}$$

overlap some of the input frequencies

$$\frac{p}{2\pi}$$

105 or

$$\frac{q}{2\pi}$$

first relay is then, neglecting the constant term αE^2 ,

$$i_1 = 2\alpha_1 E e_p + 2\alpha_1 E e_q + \alpha_1 (e_p^2 + e_q^2) + 2\alpha_1 e_p e_q$$

also

$$i_2 = 2\alpha_2 E e_p - 2\alpha_2 E e_q + \alpha_2 (e_p^2 + e_q^2) - 2\alpha_2 e_p e_q$$

$$i_3 = -2\alpha_3 E e_p + 2\alpha_3 E e_q + \alpha_3 (e_p^2 + e_q^2) - 2\alpha_3 e_p e_q$$

$$i_4 = -2\alpha_4 E e_p - 2\alpha_4 E e_q + \alpha_4 (e_p^2 + e_q^2) + 2\alpha_4 e_p e_q$$

By combining the outputs of any two relays 55 so as to add or subtract the output products, two of the output products can be retained and the other two eliminated if the E value and the α value is the same for both of the relays used. Thus assuming $\alpha_1 = \alpha_2 = \alpha$,

$$60 \quad i_1 - i_2 = 4(\alpha E e_q + \alpha e_p e_q) \quad (5)$$

eliminates all except the modulated component and the unmodified component of the modulating wave. Similarly, $i_1 - i_3$ would 65 retain only the modulation component and the unmodified carrier component. $i_1 + i_4$ would retain both combination frequency components. $i_1 - i_4$ would give the amplification terms of the separate frequencies 70 but would eliminate all the combination frequencies. Other combinations are obvious. A modulator connected in accordance with equation (5) is shown in Fig. 3 where the source 6 generates a carrier wave and is 75 neutralized in the output coils 7 and 8 unless some modulating wave, as from the circuit 9, is impressed on the modulator, assuming that the relays 10 and 11 are equivalent. Interchanging the source 6 with the 80 circuit 9 would give a form of modulator corresponding to the connection $i_1 - i_3$ in which the modulating-frequency component would be suppressed.

In practice it is difficult, if not impossible, 85 to obtain two thermionic relays with precisely the same constant α , but it is possible to make E the same for both relays. Taking into account this difference in α , $i_1 + i_4$, for example, becomes

90 If it is desired, for instance, to suppress completely the modulating frequency and not to have the unmodified carrier component unduly large, the amplitude of the carrier P should be increased and Q should be decreased in the same proportion. The modulated output which is proportional to PQ would remain unchanged. By making 115 E as small as possible and choosing α_1 as nearly equal as possible to α_4 the unmodified component of e_q may be made practically zero and the unmodified component of e_p may be made small. Similarly, by increasing Q relative to P and by making E small the unmodulated carrier frequency component could be made practically zero. A modulator to which equation (6) applies

is shown in Fig. 1 of the British Patent No. 102,503.

If it is desired to amplify several frequencies by the same relay combination

without some of the frequencies-modulating others, the push-pull type of amplifier is ordinarily used. The equation for this connection is

$$i_1 - i_4 = (\alpha_1 + \alpha_4) \left[2Ee_p + 2Ee_q + \frac{\alpha_1 - \alpha_4}{\alpha_1 + \alpha_4} (e_p^2 + e_q^2) + 2 \frac{\alpha_1 - \alpha_4}{\alpha_1 + \alpha_4} e_p e_q \right]$$

In this case E should be large to give a large output of the unmodified frequencies and the completeness with which the combination frequencies will be eliminated will depend upon how nearly equivalent α_1 is to α_4 . Increasing E within the limits imposed by equation (3) will selectively increase the amplification of the unmodified frequencies but will have no effect upon the undesired components.

By using all four relays with their input and output circuits properly related, any one of the output components can be completely isolated provided the α 's of all the tubes have negligible difference. Thus to isolate the modulated component the tubes would be connected in accordance with the relation

$$i_1 - i_2 - i_3 + i_4 = (8\alpha e_p e_q)$$

which assumes that α is the same for all four tubes. Similarly, the component of pure double frequencies could be made to occur separately. This use of four relays to secure a single output frequency component from two impressed waves is described and claimed in my copending application, Serial No. 325,731, filed September 23, 1919.

It is to be understood that the invention is not to be limited to the particular circuits or to the specific type of relay, or to the exact type of characteristic curves that have been shown and described, but only by the scope of the appended claims.

What is claimed is:

1. The method of operating a three-electrode relay for transmitting a complex wave to control selectively the transmitted current components, which comprises proportioning the fixed voltages to control the output of unmodified-frequency components relative to the combination-frequency components, and proportioning the variable applied voltages to control the unmodified-frequency components relative to each other.

2. The method of operating a three-electrode modulator to suppress unmodified current components while producing a substantially constant amount of modulated components, which comprises applying a normal negative voltage to the grid and varying either the grid voltage or the plate voltage in the negative direction until the total output current is diminished to the point where further decrease of the plate voltage begins

to cut down the production of modulated components.

3. The method of operating a three-electrode modulator to suppress unmodified current components while producing a substantially constant amount of modulated components, which comprises operating the modulator with a normal plate voltage and a grid potential adjusted to substantially such a value that a change to a more negative value will cause a decrease in the output of the modulated components.

4. The method of controlling modulating discharge devices to transmit selectively the different frequency-components which comprises connecting said relays in balanced relation, and diminishing the normal effective constant voltages to the point where further decrease begins to cause distortion of the combination frequencies.

5. The method of suppressing the output of unmodified frequency-components in a balanced modulator consisting of discharge devices, which comprises connecting said devices so as approximately to eliminate the transmission of said components, and operating said modulator near the lower limit of the discharge current value for which the output of modified-frequency components remains substantially constant.

6. In a modulator for modulating a carrier wave by a modulating wave, said modulator comprising discharge devices, the method of suppressing one of said waves while keeping the component of modulated current constant, which comprises connecting said relays so as approximately to eliminate the transmission of the undesired wave, operating said modulator near the lower limit of the discharge current value at which the modulated current component remains substantially constant, and making the amplitude of the undesired wave small in comparison with that of the other wave, still keeping their product practically constant.

7. In a balanced modulator for modulating a carrier wave by a modulating wave, the method of suppressing one of said waves while keeping the component of modulated current substantially constant, which comprises decreasing the amplitude of the wave to be suppressed, increasing the amplitude of the other wave in the same proportion, and operating the modulator near the lower limit of the discharge current range within

- which the modulated current component remains practically constant.
8. The method of operating thermionic relays to control suppression of certain frequency-components, which comprises connecting said relays so as to neutralize said components except for inherent differences in the relays, and proportioning the applied voltages which affect selectively the production of said components so as to cause approximately minimum ratio of said components to desired components.
9. The method of operating thermionic relays to control the suppression of certain current components, which comprises proportioning the fixed applied voltages to control selectively the production of the unmodified frequency components, and proportioning the amplitudes of the applied waves to determine the minimum ratio of certain of the unmodified-frequency and multiple-frequency components to the combination-frequency components.
10. The method of operating thermionic relays for which the equivalent fixed voltages may be represented by E and the impressed waves by $P \cos pt$ and $Q \cos qt$, respectively, which comprises proportioning E to give the desired production of unmodified-frequency components, and in proportioning P and Q independently to control the production of one multiple-frequency component relative to another and independently to control the production of the combination-frequency components $PQ \cos pt \cos qt$, substantially as described.
11. The method of controlling two modulator relays to secure a substantially pure output wave of combination frequencies which comprises opposing the transmission characteristics of one relay for unmodified frequencies to that of the other relay, and in applying the same fixed voltages to both relays of such value that the net resultant transmission of the unmodified frequency components is made substantially a minimum while the output of the combination frequency components is substantially undiminished.
12. In balanced relay systems for suppressing transmission of undesired frequency components in which the transmission property of one relay for undesired components is made to oppose that of another relay, the method of suppressing the undesired frequencies which are not suppressed by virtue of the differences in the respective relay transmission properties, comprising controlling the applied voltages to affect the transmission of the undesired components substantially independently of the other components.
13. In frequency modifying relay systems, the method of controlling selectively the output of unmodified frequency components comprising controlling the magnitude of the applied voltages which affect the output of the unmodified components practically independently of the other components substantially as described.
14. In the use of frequency-modifying relays having a direct current voltage operating range within which the output of complex frequency components is substantially the same for the same input of variable voltages, the method of controlling the output of unmodified-frequency components comprising varying the applied direct current voltages within said voltage operating range.
15. In a modulator, a discharge device having a source of space current, a source of grid potential, and sources of waves for modulation, said source of space current being of such voltage as to give the desired conductivity to said device, and said source of grid potential having a negative voltage approximating the smallest negative value for which the output of the modulation current component is dependent on said grid voltage.
16. In balanced thermionic relay systems in which a transmission characteristic of one relay for current component of unmodified frequency is opposed to that of another relay, means for compensating for differences in said characteristics comprising fixed operating voltages for said relays of such magnitude that the unmodified frequency output is made substantially a minimum independently of the output of the other components.
17. In balanced relay systems, comprising two thermionic relays in which for given input waves the output wave of each relay contains components of the same frequency as the input waves and components of complex frequencies, and in which the relays are so connected that the transmission properties of said relays for the unmodified frequency components are opposed, means for minimizing the effects of differences in said properties upon the transmission of unmodified frequency components comprising fixed operating voltages for said relays of the smallest equivalent value for which the production of the components of complex frequencies in the desired amount is still obtained.
- In witness whereof, I hereunto subscribe my name this 27th day of September, A.D., 1919.

RALPH V. L. HARTLEY.
